Attorneys.

UNITED STATES PATENT OFFICE.

L ALBERT SAMSTAG, OF NEW YORK, N. Y.

DESIGN FOR A HAIR-BRUSH OR SIMILAR ARTICLE.

57,154.

Specification for Design.

Patented Feb. 22, 1921.

Application filed January 3, 1920. Serial No. 349,341. Term of patent 14 years.

To all whom it may concern:

Be it known that I, L ALBERT SAMSTAG, a citizen of the United States, residing at 9 West 74th St., in the borough of Manhattan, city of New York, State of New York, have invented a new, original, and ornamental Design for a Hair-Brush or Similar Article, of which the following is a specification, reference being had to the accompanying drawing, forming part thereof.

The figure is a plan view of a hair brush, showing my new design.

I claim—

The ornamental design for a hair brush or similar article substantially as shown.

L ALBERT SAMSTAG.
